UNITED STATES PATENT OFFICE

2,018,822

METHOD OF MAKING SHOES

Lewis F. Weber, New Rochelle, N. Y., assignor to
United Shoe Machinery Corporation, Paterson,
N. J., a corporation of New Jersey

Application May 22, 1933, Serial No. 672,175

12 Claims. (Cl. 12—142)

This invention relates to the manufacture of shoes and, in some aspects, more particularly to the manufacture of turn shoes. In the manufacture of turn shoes an upper and a sole member provided with an inside channel are assembled on a last wrong side out and the upper secured in lasted relation to the sole by temporary fastening means before it is sewed to the sole. In the lasting operation it has been heretofore a common practice to fasten the upper to the sole along the sides and at the toe end by tacks which are driven through the margin of the upper and into the body portion of the sole in directions toward that face of the sole which is outermost in the finished shoe. While the use of tacks for lasting the toe ends has been entirely satisfactory in a machine designed particularly for that purpose, their use as temporary fastening means for lasting the sides has been objectionable because of the inability of the workmen, despite the exercise of great care, to insure that the tacks will be inserted in such manner as not to penetrate entirely through the sole and thus leave tack holes which are likely to result in unsightly stains visible on the outer face of the sole of the finished shoe. Moreover, since in shoes of the type above referred to, the upper is secured in lasted relation, both temporarily and permanently, close to the plane of that face of the sole which forms in the finished shoe the inside surface which engages the foot of the wearer of the shoe, it is particularly desirable that no objectionable ridges or projections remain in the inside of the finished shoe and that the temporary lasting fastenings be entirely removed from the shoe since one or more of the temporary fastenings, if permitted to remain in the shoe, would be likely to become a source of annoyance or injury to the wearer of the shoe.

It is an object of the present invention to provide an improvement in methods of making turn shoes in which the upper is secured temporarily in lasted relation to the sole by fastenings which do not penetrate the body portion of the sole thereby eliminating the objectionable use of side lasting tacks at the shanks and foreparts of the shoes and the danger of tack holes and visible stains resulting from the use of such tacks.

In one aspect the invention consists in securing wrong side out the upper of a turn shoe temporarily in lasted relation to the sole by lasting fastenings inserted through the upper and a lip on the sole in locations above the plane of the central portion of the sole. In another aspect the invention consists in securing the upper

temporarily in lasted relation to the sole by lasting fastenings which are inserted through the upper and a lip on the sole and then permanently to the sole by a thread seam which is arranged to draw the upper farther inwardly over the sole beneath said lip and against a shoulder on the sole to increase the tension of the upper over the last and to cause said upper to force said lip upwardly, to raise the temporary lasting fastenings above the path of the inseam trimming knife, and inwardly to force the flap of the inside channel downwardly below the path of said knife to provide the shoe after the inseam trimming operation has been performed with a plane flat surface which forms in the finished shoe the inside surface which engages the foot of the wearer of the shoe. As illustrated, the sole member is provided in addition to the usual inside channel with an outside channel so formed as to provide an upstanding peripheral lip and an upper attaching shoulder which is located farther inwardly from the edge face of the sole than the outer face of the lip. The outside channel may be conveniently formed by providing the marginal portion of the sole with a slit directed inwardly from its edge face to within a short distance of the end of the downwardly and outwardly inclined inside channel and then upwardly toward that face of the sole in which the inside channel is formed. The outside channel is then opened to expose the upper attaching shoulder and to form an upstanding peripheral lip which overlies the shoulder and to which the upper is secured, as illustrated herein, by lasting fastenings comprising fine wire staples which are inserted through the upper and the upstanding lip and are clinched on the back of the lip. In the inseaming operation as the upper is drawn farther inwardly over the bottom of the sole beneath said lip and against the upper attaching shoulder by the thread seam the lip is forced upwardly and inwardly by the pressure of the upper thereon, thereby insuring that all the staples will be located above the path of the inseam trimming knife and that the flap of the inside channel will be forced downward beneath the path of said knife to close the inside channel.

In another aspect, my invention comprises a new article of manufacture consisting of a sole member having an inside channel and an outside channel formed to provide a lip adjacent to the edge face of the sole to receive the temporary lasting fastenings and an upper attaching shoulder which is located farther inwardly from the edge face of the sole than the outer face of said

lip. The outside channel is preferably formed by cutting the sole inwardly from its edge face to within a short distance of the end of the downwardly and outwardly inclined inside channel 18 and then upwardly to form, before the lip turning operation, an unexposed upper attaching shoulder. The outside channel is opened to provide the shoe with an upstanding peripheral lip which serves to receive the temporary lasting fastenings and which is later trimmed off below the fastenings to provide the sole with a plane flat tread surface.

A sole member having the construction above described may be employed with similar advantages as an insole for welt shoes particularly for welt shoes in which little or no filler is to be employed.

The invention will now be more particularly described by reference to the accompanying drawing and thereafter pointed out in the claims.

In the drawing,

Fig. 1 is a perspective view of an improved sole member for a shoe which may be employed in carrying out the present invention;

Fig. 2 is a cross-section on an enlarged scale of the sole member shown in Fig. 1 before the lip turning operation is performed;

Fig. 3 is a view similar to Fig. 2 but showing the location of the peripheral lip and upper attaching shoulder after the lip turning operation has been performed;

Fig. 4 is a view illustrating the step of attaching the upper of a turn shoe to the peripheral lip on the sole in the side lasting operation;

Fig. 5 is a view in cross-section showing the shoe after the side lasting operation has been performed;

Fig. 6 is a view in cross-section showing the shoe after the upper has been secured permanently to the sole by a thread seam;

Fig. 7 is a view in cross-section showing the shoe after the inseam trimming operation has been performed;

Fig. 8 is a view partly in perspective and partly in cross-section showing the forepart of the shoe after the shoe has been turned and mounted on its second last; and

Fig. 9 is a view in cross-section of a Goodyear Welt shoe after the upper and welt have been secured to a sole member by stitching.

As illustrated in the drawing, the materials of the turn shoe comprise a sole 10 and an upper consisting of the usual upper leather 12 and lining 14. The shoe materials are assembled on a last 16 wrong side out after which the lasting operation is performed preferably first at the toe-end portion of the shoe then along the sides of the shoe and finally at the heel end, the shoe herein shown being one of the sewed seat type.

For the toe-end lasting operation it is contemplated that a combined pulling-over and toe lasting machine may be advantageously used of the type disclosed in Letters Patent of the United States No. 1,280,613, granted on October 1, 1918

upon an application of Orrell Ashton, in which the upper is first subjected to a lengthwise pull and then wiped inwardly over the sole around the toe end and secured in lasted position by tacks, the machine being so constructed that the tacks are driven without any substantial danger of penetrating entirely through the sole.

As shown particularly in Fig. 1 the sole 10 is provided with an inside channel 18 to receive the stitching 20 whereby the upper is secured permanently to the sole along the sides and around the

ends of the shoe after the lasting operations have been performed. By reference to Figs. 2 and 3 it will be observed that the sole 10 in addition to the usual inside channel 18 is provided also for purposes of this invention with an upper attaching shoulder 22 and a lip 24 above said shoulder to which lip the upper is secured in lasted relation to the sole along the sides of the forepart and shank portion of the shoe by temporary fastenings comprising as herein illustrated fine wire staples 26 which are inserted through the upper and the lip 24 in locations above the plane of the central portion of the sole. The upper attaching shoulder 22 and lip 24 are formed by providing the sole with an outside channel or slit 15 28 directed inwardly from the edge face of the sole in parallel relation to the outer face of the sole. The slit 28 extends inwardly to within a short distance of the end of the downwardly and outwardly inclined inside channel 18 and then upwardly toward that face of the sole in which the inside channel is formed in a plane parallel to the edge face of the sole to form the upper attaching shoulder 22. The sole member is thus provided with a uniform extension or feather and an upper attaching shoulder which serves accurately to locate the thread seam 20.

While so far as the present invention is concerned the lasting of the upper along the sides of the shoe may be performed in any known or suitable manner, in the commercial practice of the present invention, as herein illustrated, this operation will preferably be performed by a machine of the type disclosed in Letters Patent of the United States No. 1,796,451, granted March 17, 1931, upon an application of George Goddu. In the use of such a machine the shoe is presented by the operator in engagement with a work rest 30 (Fig. 4) provided with a finger 32 which is arranged to enter the inside channel 18 and to serve as a gage to assist the operator in positioning the shoe with the work engaging face of the work rest 30 in engagement with the inside face of the lip 24. While the shoe is thus positioned the upper is pulled lengthwise of the last and inwardly over the sole by a gripper 34 and is then pressed inwardly against the outer face of the lip 24 by a staple guiding nozzle 36. After the upper has thus been pressed against the lip in a position opposite the work rest 30 the staple 26 is driven through the upper and lip by a driver 38 and is clinched by the work rest which serves also as an anvil. It will be understood that in the side lasting operation the upper is worked successively in different locations along the sides of the shoe into lasted relation to the sole and is secured temporarily in lasted position in each location by the staple 26. After the shoe has been lasted at the toe and the sides, the heel end of the upper may be and preferably is shaped to the heel end of the last and its marginal portion wiped inwardly over the feather of the sole and against the shoulder 22 before the lasted upper is secured permanently to the sole in the subsequent inseaming operation in accordance with the method disclosed in Letters Patent No. 1,737,727, granted Dec. 3, 1929 on an application of Herman Newmann. A machine adapted for use in practising the method disclosed in the above-mentioned Newmann patent is disclosed in Letters Patent No. 1,770,976, granted July 22, 1930 on an application of Joseph Fausse. After the heel end of the shoe has been shaped to the heel end of the last the upper is secured permanently to the sole by the thread seam 20, which may be a hand sewed

seam or one made by turn sewing machines of the usual types. The lasting tacks are then removed at the toe and the surplus marginal portion of the upper and the lip 26 are trimmed off in the plane 5 of the central portion of the sole thereby removing the staples, Fig. 7. The last is then withdrawn from the shoe and the shoe is turned and mounted on a second last 40 after which the heel end of the shoe may be reshaped by the method disclosed 10 in the Newmann patent above-mentioned and the remaining manufacturing operations are performed as usual.

It will be seen by reference to Figs. 1, 2 and 3 that before the lip turning operation is performed 15 the upper attaching shoulder 22 is unexposed and that after the channel 28 has been opened the shoulder 22 is located farther inwardly from the edge face of the sole than the outer face of the lip 24 to which the upper is secured temporarily in 20 lasted position by the staples 26. Accordingly in the sewing operation not only is the tension of the upper over the last increased as the upper is forced farther inwardly over the bottom of the shoe by the tightening of the stitch 29, but since 25 the lip 24 overhangs the shoulder 22 the upper and lining as they are drawn against the shoulder and the feather of the sole beneath the lip act to force the lip upwardly and inwardly. As the 30 lip is forced upwardly and inwardly by the pressure of the upper against it the staples are raised and the inside channel flap 42 is forced downwardly to close the inside channel 18 thus permitting the inseam to be trimmed as closely as 35 desired to the plane of the sole without danger of damaging the thread seam 20. Subsequently and as illustrated in Fig. 7 the surplus margin of the upper and the lip 24 together with the staples are 40 trimmed off substantially in the plane of the central portion 44 of the sole thereby providing the sole member with a plane flat surface free from projections or ridges, which surface in the finished shoe forms the inside surface for the foot of the wearer.

While the invention has been described with 45 particular reference to the manufacture of turn shoes it will be recognized that, in some features, it is not thus limited but is applicable to the manufacture of other types of shoes, for example, Goodyear Welt shoes of the type in which an out- 50 sole is cement attached to a narrow and preferably a thin welt which is secured to the shoe upper and a sole member by a thread seam. It is particularly desirable in shoes of this type to trim the inseam close to the plane of the sole member to 55 which the upper and welt are attached to facilitate the cement outsole attaching operation.

Referring to Fig. 9 the sole member of a Good- 50 year Welt shoe is indicated at 58, the upper at 52, the welt at 54, and the last at 56. The sole mem- 55 ber is provided with an inside channel 58 to receive a thread seam 60 and with an outside chan- nel formed to provide an upper attaching shoulder 62 and a lip 64 to which the upper is secured in the lasting operation by staples 66. While the 60 outside channel may be formed substantially the same as the channel 28 above described, if desired the shoulder 62 may be located different distances from the edge face of the sole to accommodate welts of different widths, and the thickness of the reduced marginal portion of the sole may vary to 65 accommodate welts of different thicknesses. As the upper and welt are drawn inwardly against the shoulder 62 beneath the lip 64 by the thread seam 60 the lip 64 is forced upwardly thereby 70 raising the staples 66 and is also forced inwardly

to close the inside channel 58. Thereafter the surplus margin of the upper and the lip 64 in- 75 cluding the staples are trimmed off on the line 68 substantially in the plane of the central por- tion of the sole 58 thereby providing the sole with a plane flat bottom surface best fitted for the reception of an outsole without the use of a filler though a piece of fabric or the like may be located between the insole and outsole to prevent squeaking.

Having thus described the invention what I 10 claim as new and desire to secure by Letters Patent of the United States is:

1. That improvement in methods of making turn shoes which consists in assembling shoe ma- 15 terials wrong side out upon a last, said materials comprising an upper and a sole having an inside channel and a lip adjacent to the edge face of the sole, securing the upper temporarily in lasted relation to the sole by fastenings inserted 20 through the upper and the lip, thereafter per- manently securing the lasted upper to the sole by stitching passing through the upper and the substance of the sole, trimming off the lip and the surplus portion of the upper close to the 25 stitching thereby removing the temporary fas- tenings, removing the last, and turning the shoe.

2. That improvement in methods of making turn shoes which consists in assembling shoe 30 materials wrong side out upon a last, said ma- 35 terials comprising an upper and a sole having an inside channel and an outside channel formed to provide a lip and a shoulder, securing the up- per to the sole by metallic fastenings inserted through the upper and said lip above the shoul- 40 der, thereafter permanently fastening the lasted upper to said shoulder, trimming off the surplus portion of the upper and the lip above the shoul- der including the metallic fastenings, removing the last, and turning the shoe.

3. That improvement in methods of making turn shoes which consists in assembling shoe materials wrong side out upon a last, said ma- 45 terials comprising an upper and a sole having an inside channel, an upper attaching shoulder, and 45 a lip adjacent to the edge face of the sole and overhanging said shoulder, securing the upper temporarily in lasted relation to the sole by fas- tenings inserted through the upper and said lip, thereafter drawing the upper farther inwardly 50 over the sole beneath said lip and against said shoulder by a thread seam arranged to secure the upper permanently to the sole, removing the sur- plus portions of the upper and of the lip, includ- 55 ing the fastenings which extend above the plane of the sole, removing the last, and turning the shoe.

4. That improvement in methods of making turn shoes which consists in assembling shoe ma- 60 terials wrong side out upon a last, said materials comprising an upper and a sole having an inside 65 channel, a lip adjacent to the edge of the sole, and an upper attaching shoulder located farther inwardly from the edge of the sole than the outer face of said lip, securing the upper temporarily 70 in lasted relation to the sole by fastenings in- 75 serted through the upper and said lip in locations above the plane of the central portion of the sole, thereafter stitching the upper to said shoulder to secure it permanently to the sole, trimming off the lip and the surplus portions of the upper 80 including the fastenings, removing the last, and turning the shoe.

5. That improvement in methods of making turn shoes which consists in assembling shoe 75

- materials wrong side out upon a last, said materials comprising an upper and a sole provided with a peripheral lip and an upper attaching shoulder located below said lip in a plane parallel to the plane of the edge face of the sole and farther inwardly from said edge face than the outer face of said lip, working different portions of the upper successively into lasted relation to the sole and securing each overworked portion temporarily in lasted position by staples inserted through the upper and said lip above the plane of the central portion of the sole with the legs of the staples clinched on the inner face of said lip, thereafter permanently securing the lasted upper to said shoulder by stitching, trimming off the lip and the surplus portion of the upper in the plane of the central portion of the sole thereby removing the staples, removing the last, and turning the shoe.
6. A new article of manufacture comprising an unattached sole member having an inside channel, an upper attaching shoulder extending around the periphery of the sole, and an upwardly extending lip overhanging said shoulder, said lip having a bottom face extending transversely of said shoulder.
7. A new article of manufacture comprising an unattached sole member provided with an inside channel and an outside channel formed to provide a lip adjacent to the outer edge of the sole, and an upper attaching shoulder located farther inwardly from the edge of the sole than the outer face of said lip and connected thereto by a transversely extending face.
8. A new article of manufacture comprising an unattached sole member having an inside channel and an outside channel formed to provide an upstanding peripheral lip adjacent to the edge face of the sole and an upper attaching

shoulder below said lip, said shoulder being formed on a portion of the sole undisturbed by the turning of the lip and located farther inwardly from said edge face than the outer face of said lip and in a plane parallel to said edge face. 5

9. A new article of manufacture comprising a sole member provided with an inside channel and an outside channel formed to provide a lip and an upper attaching shoulder which, before the lip-turning operation, extends in a direction transverse to the lip. 10

10. A new article of manufacture comprising a sole member having an inside channel and a slit formed in the margin of the sole, said slit extending inwardly from the edge face of the sole and having a portion extending upwardly toward the channeled face of the sole in parallel relation to said edge face to form an upper attaching shoulder which, before the lip turning 20 operation, is unexposed.

11. That improvement in methods of making turn shoes which consists in assembling shoe materials wrong side out upon a last, said materials comprising an upper and a sole, securing the upper to a temporary lasting element on the sole, permanently securing the upper to the sole, removing the temporary lasting element, and then removing the last and turning the shoe. 25

12. A new article of manufacture comprising a sole member having an inside channel and a slit formed in the margin of the sole, said slit having a straight portion extending inwardly from the edge face of the sole, and a portion extending transversely of said straight portion to 30 form an upper attaching shoulder after the lip turning operation. 35

LEWIS F. WEBER.
